UNITED STATES PATENT OFFICE.

EDWARD P. MITCHELL, OF CONNEAUT, OHIO, ASSIGNOR TO THE CLEVELAND GAS AND ELECTRIC FIXTURE COMPANY, OF CLEVELAND, OHIO, A CORPORATION OF OHIO.

SHADE AND REFLECTOR FOR ELECTRIC LAMPS.

981,585.

Specification of Letters Patent. Patented Jan. 10, 1911.

Application filed January 27, 1909, Serial No. 474,380. Renewed December 1, 1910. Serial No. 595,153.

To all whom it may concern:

Be it known that I, EDWARD P. MITCHELL, a citizen of the United States, residing at Conneaut, in the county of Ashtabula and 5 State of Ohio, have invented a certain new and useful Improvement in Shades and Reflectors for Electric Lamps, of which the following is a full, clear, and exact description.

10 The object of the present invention is to provide an electric lamp fixture suitable for holding the lamps and the shades or reflectors therefor.

More particularly my invention relates to 15 a fixture for use with such reflectors as those of the type commonly called holophane in which the relative position of the reflector to the center of luminosity of the light is a factor of the greatest moment in determining where the rays of reflected light shall 20 be cast.

The distance of the various parts of the reflectors from the center of luminosity has such a marked effect, that heretofore whenever 25 ever a change in effect has been desired a new reflector has been used; the common practice being for the user to notify the dealer precisely the distribution of reflected light desired, upon which, a proper selection 30 of reflector is made by the dealer. I have discovered, however, that, by making the holder for the reflector adjustable along its axis relative to the lamp bulb, it is possible to obtain the various effects desired, within 35 reasonable limits; and I have devised a means by which this may be done without interfering in any manner with the connections of the electric bulb or impairing the efficiency of any part of the fixture.

40 An embodiment of my invention is described in the following specification with reference to the accompanying drawings in which:

Figure 1 is a side elevation partly broken away and partly in section showing the invention applied to a crown fixture, and Fig. 45 2 is an elevation showing the reflector holder detached.

The structure shown in the drawings comprises a ventilated crown made up of upper 50 and lower portions A', A² suitably secured together by bayonet joint in such manner that when the said joint is loosened the upper section may drop down over the lower section, thus leaving the securing foot B

exposed so that it may be applied to the ceiling or wall.

The lower section of the crown is secured to a three-legged spider C carried upon the central supporting stem B'. This spider will 60 hold the lower section rigidly in place. The supporting stem is hollow and threaded at its lower end B² to receive the conventional form of electric lamp socket shown in dotted lines, the electric connections being carried 65 through this hollow stem.

It will be noted that the stem is threaded in its immediate portion B³ and carries a holder D for the reflector, this holder having a nut D' at its upper end so that it is adjustable up and down on said stem. The neck of the shade, indicated in dotted lines is secured to the lower end of the holder by means of short set screws D² or any other suitable device.

The lower crown section has an inwardly projecting flange A³ closely surrounding a cylindrical portion D³ of the reflector holder, making a neat fit therewith. It will be seen that when it is desired to raise or lower 80 the reflector relative to the center of luminosity of the lamp, which is fixed through its socket to the supporting stem, it will be necessary to do nothing more than rotate the reflector and its holder to secure the desired result, since the nut D' fixed to the upper end of the reflector holder will ride up and down over the threads on the stem. The range of movement necessary is comparatively limited, and it will not be necessary to 85 make the cylindrical portion D³ or that portion of a holder which fits closely to the lower portion of the crown section, of very great length, but it is desirable that it should be of a length sufficient that the neat appearance will not be affected by the relative position of the parts.

Having thus described my invention, I claim:

1. A fixture for electric lamps comprising 100 a stem having a lamp socket secured thereto, and a reflector holder incasing said lamp socket and movable thereover, said holder mounted on said stem having means for holding a reflector, said holder being adjustable endwise upon said stem.

2. An electric lamp fixture comprising 105 a crown piece having an extension shell, a lamp socket and means for supporting the same, a holder for a reflector and means for 110

obtaining relative adjustment between the reflector holder, the lamp socket, and the said extension shell.

3. A fixture for electric lamps comprising a supporting stem having a lamp socket thereon, a reflector holder adjustable relatively to said stem, and a surrounding shell, the edge of which closely approaches the adjustable reflector holder and permits longitudinal movement of the said holder.

4. An electric lamp fixture comprising a supporting stem, said stem carrying a lamp socket and a reflector holder adjustable relative to each other, a spider on said stem, and a shell secured to said spider, the lower edge of the shell closely approaching the reflector holder.

5. An electric lamp fixture comprising a stem and a lamp socket, means for support-

ing the latter, a holder for a reflector mounted on said stem and movable over said lamp socket, and means for obtaining relative adjustment between the reflector holder and the lamp socket.

6. In a fixture for lamps, a supporting stem adapted to be secured to the ceiling, wall, or the like, a crown piece secured on said stem and provided with an extension shell, a lamp socket secured on one terminal of the said stem, and a reflector holder adjustable on said stem within the extension shell.

In testimony whereof, I hereunto affix my signature in the presence of two witnesses.

EDWARD P. MITCHELL.
